UNITED STATES PATENT OFFICE.

EDWARD HENRY ALBERT LEGGATT, OF WOODFORD GREEN, ENGLAND.

DART BOARD OR LIKE TARGET.

Application filed January 29, 1923. Serial No. 615,652.

To all whom it may concern:

Be it known that I, EDWARD HENRY ALBERT LEGGATT, a subject of the King of Great Britain, residing at Greenlea, Woodford Green, Essex, England, have invented a new or Improved Dart Board or like Target, of which the following is a specification.

This invention relates to dart boards or like targets.

Heretofore such targets have been made of wood or cork with metal wires stretched upon the wood or cork to divide the target into spaces which are usually marked with different values. Such targets are difficult to stock as they are affected by the amount of humidity in the atmosphere. It is therefore usual periodically to soak them in water, besides which it is found that the darts are often diverted by the metal wires.

According to this invention I construct a dart board of material which remains plastic permanently or for a considerable period. Such plastic material may be bought in the open market, being sold under the name "Nodor" or "Plasticine" amongst others.

The accompanying drawing shows a target made in accordance with this invention. Figure 1 is a front elevation and Figure 2 a transverse section.

a is a thin metal frame mounted upon a

plate *b*, the frame consisting of two rings *c* and *d* and radial bars *e* forming a number of compartments. In the frame is the central bull's eye, which, together with the frame is filled with plastic material. The compartments may be numbered so that a hit with a dart is given a different value, according to the compartment it strikes.

Such a target is unaffected by variations of the atmosphere and the metal plates being thin the darts cannot be stopped but are only slightly diverted if they should strike them.

What I claim is:—

1. A dart board consisting of a plate, a metal frame fixed to the plate, and adapted to form compartments, and a filling of plastic material in the frame.

2. A dart board consisting of a plate, two rings fixed to the plate, radial bars adapted to form compartments, and a filling of plastic material between the rings.

3. A dart board consisting of a plate, two rings fixed to the plate, the smaller ring forming a bull's eye, radial bars adapted to form compartments and a filling of plastic material between the rings and in the bull's eye.

In testimony that I claim the foregoing as my invention I have signed my name this 18th day of January, 1923.

EDWARD HENRY ALBERT LEGGATT
